KNITTING MACHINE

Harry A. Shields, Grand Rapids, Mich.; Eugene Richards, administrator of said Harry A. Shields, deceased, assignor to Grand Rapids Textile Machinery Company, Grand Rapids, Mich., a corporation of Michigan

Application July 9, 1932, Serial No. 621,654

12 Claims. (Cl. 66—137)

This invention relates to an attachment for circular knitting machines, such machines being utilized in knitting tubes of fabric, and the attachment of my invention is primarily concerned with the production of reverse plating on a circular knitting machine, and with the provision of means whereby an indefinite number of patterns may be produced.

The invention is concerned with mechanism for automatically changing the position of threads, usually of different colors, running to the needles so that the engagement of the needles with the thread will place the thread of one color at the upper end of the needle and of another color below the first thread, and on a change of position of the guides which carry the thread or yarn, which guides are automatically periodically operated through the mechanism of my invention, the positions of the threads in the needle are reversed, thereby automatically changing the thread or yarn of one color from the inner side of the tube of fabric knitted, to the outer side thereof and vice versa.

It is a further object and purpose of the invention to control the alternating movements of the thread guides by means of cams and, through different shapes and forms of cams, provide for many different patterns. Furthermore the mechanism for driving the cams may be either a direct drive from the rotating mechanism of the knitting machine or an eccentric drive and the speed of rotation of the cams may be increased or diminished by changing gears whereby patterns of the same kind may be greatly varied in size and shape, all being readily attained with the relatively simple and economically constructed device of my invention.

An understanding of the invention may be had from the following description, taken in connection with the accompanying drawings, in which,

Fig. 1 is a somewhat diagrammatic plan view illustrating the application of my invention to a circular knitting machine.

Fig. 2 is a fragmentary enlarged plan view showing one of the units of my invention, a plurality of which are located around the table of the knitting machine.

Fig. 3 is a fragmentary enlarged transverse vertical section through a side of a circular knitting machine, showing one of the units of the reverse plating mechanism of my invention in side elevation.

Fig. 4 is an end elevation of the drive gearing utilized with the invention.

Fig. 5 is a fragmentary elevation of one of the

devices of my invention, certain parts being shown in cross section.

Fig. 6 is a fragmentary elevation illustrating the thread or yarn guides in one of their positions with respect to each other.

Fig. 7 is a fragmentary enlarged cross section similar to Fig. 3, showing the position of the threads with reference to the needles before the needles are drawn downwardly to perform a knitting operation, and

Figs. 8 to 12, inclusive, are views illustrating different types of patterns which may be produced with my invention, it being understood that an indefinite number of patterns of differing characters may be produced with changes in cams, gearing, timing of rotation of the cams and the like.

Like reference characters refer to like parts in the different figures of the drawings.

In a circular knitting machine there is provided an outer horizontal ring or table 1 which is stationary in the machine within which is mechanism for continuous rotation, including a ring 2 horizontally located underneath and bearing against the underside of the table 1, and having a downwardly extending annular gear 3 at its outer edge. At the inner side of the ring 2 is an upwardly extending member 4 provided with guides 5 for needles 6. The needles turn with the part 4 and the ring 2 with which it is connected, and move inside of a ring 7 at the side of which adjacent the needles is a needle operating cam 8. The cam 8 is a continuous plate with a slot therein into which laterally extending projections 9 from the needles extend. As the needles turn about a vertical axis with respect to the stationary cam plate 8, the same come to downwardly inclined portions of the cam slots thereby drawing the needles downwardly for an interval as best indicated in Fig. 6. The needles are provided with pressers 10, normally held in

the position shown in Figs. 3 and 7 by a continuous coiled spring 11 which passes around the lower ends of all of the pressers 10, being seated in notches therein as shown, which pressers are automatically operated at the proper time to act in conjunction with the needles to cast off the loops knitted. The specific construction of a circular or tubular knitting machine is not attempted to be described as such type knitting machine is a very well known and fully developed machine, but only enough of the machine is illustrated and described to set forth the environment in which my invention is of utility.

At a plurality of spaced apart stages around the table 1 are vertical supporting posts 12 ex-

tending upwardly from base segments 13, a number of which are joined together end to end around and secured to the machine, each of the base segments 13 being designed to carry one of 5 the devices of my invention. A shaft 14 is mounted on the support 12 and an adjacent lug 15 extended upwardly from a base segment 13 (Fig. 5) carrying a gear 16 which in turn drives a gear 17 above it. The gear 17 and a cam wheel 18 are 10 both mounted for rotation on a horizontal shaft rotatably mounted at the upper portion of the support 12. The cam wheel 18, as shown in Fig. 3, has three equally spaced cams 19, but it is to be understood that the cam wheel may have 15 a greater number of projecting cams spaced either equal or unequal distances apart, and the projecting cams 19 may be of the same or of different lengths, it being designed that the cam wheels 18 may be interchangeable on the shaft carrying 20 the same, different cams being used for different patterns which are to be knitted.

An arm 20 is pivotally mounted at its lower end on a rock shaft 21 at the upper end of the support 12, and at the upper end of the arm 20 25 a supporting plate 22 is permanently secured and extends inwardly, substantially in a horizontal plane; nearly to the needles 6. Supporting posts 23 on the table 1 carry ring members 24 and 25 as parts of the knitting machine, and it is 30 across the horizontal upper side of the member 25 that the plate 22 extends; and an adjusting screw 26 may thread downwardly through the plate 22 to bear at its lower end against the ring member 25 for adjustably locating the plate 22.

35 It is of course understood that in the description being made of a unit, such description applies to all of the several units which are located in spaced apart relation around the knitting machine. At the inner end of the supporting plate 40 22 are bearings 27 and at the outer end bearings 28 for rotatably carrying spaced apart rock shafts 29 and 30, each of which at its outer end has a lever 31 adjustably secured thereto. As shown in Fig. 5 the the levers may be adjusted 45 about the axis of the shafts 29 and 30. The levers extend toward each other and are provided at their adjacent ends with heads 32 the lower sides of which bear against the upper end of a head 33 extending from an arm 34 pivotally mounted at its inner end on an extension 35 to the support 12 the lower end of the head 33 bearing against 50 the cam wheel 18, whereby when one of the projecting cams 19 rides underneath the head 33 it lifts the same and tilts the two levers 31, one in a clockwise direction and the other in a counter-clockwise direction. On the cam projection 19 moving away from the head 33 and permitting the arm 34 to drop, levers 31 return to their 55 original positions or until stopped by the engagement of their outer ends against the lower ends of adjusting screws 36 threaded through the plate 22 (Fig. 5). The upper sides of the heads 32 described are pressed against by spring plungers housed within a housing 37, as shown in Fig. 5, 60 so as to cause the levers to positively follow the cams or drop therefrom and rock the rock shafts 29 and 30.

65 The inner ends of rock shafts 29 and 30 each carry yarn or thread guides of the shape shown 70 in Fig. 6. That is, from each of the shafts 29 and 30 an arm 38 extends radially, joining with which is an elongated guide bar 39, one end thereof carrying a guide sleeve 40 while the other end has an opening 41, the bars 39 being longitudinally recessed to provide elongated troughs 75

42. The yarns or threads 43 and 44 come from the bobbins carried by the knitting machine, pass through the guide sleeves 40, thence lengthwise of the troughs 42 and through the openings 41 to be engaged by the needles. 5

It is evident that upon the rock shafts 29 and 30 rocking in different directions, for example, in Fig. 6, the rock shaft 30 being moved in a counterclockwise direction and the shaft 29 in a clockwise direction, the relative positions of the threads or yarn 43 and 44 will be changed. In the position shown in Fig. 6 the yarn at 43 is located above the yarn 44. But on rocking the shafts this position of the yarn or thread is changed. This occurs when a cam, such as 19, 15 passes underneath the head 33 of the lever 34. When the cam passes from under said head 33, permitting the same to drop and the levers 31 to return to initial position, the position of the yarn or threads 43 and 44 will again be that shown 20 in Fig. 6. And with the continued operation of the knitting machine it is evident that the position of the yarn 43 and 44 in the knitted fabric will be periodically changed or reversed from the inner to the outer side of the tubular fabric 25 produced and vice versa.

30 The yarns or threads 43 and 44 may be of different colors or of different material and the extent of the reversal of the yarns from one side of the tubular knitted fabric to the other will be 30 dependent upon the shape of the cams, their lengths and the speed of rotation of the shaft which carries the cam wheel 18.

35 Driving the cams is accomplished by a gearing connection with the ring gear 3. A bracket support 45 of U-shape is located over the edge of the table 1 in proper position and may be detachably clamped thereto by a set screw 46. A horizontal sleeve 47 carries a shaft at the inner end of which is a gear 48 meshing with the ring gear 40 3. At the outer end of the shaft is a pinion 49 in mesh with a gear 50 which is carried on an arm 51 adjustably mounted on a second arm 52 extending from the supporting bracket 45, the upper end of the arm 51 having a slot 53 while the arm 52 is equipped with a set screw to go through said slot permitting adjustment of the supporting arm 51 which carries the pinion 50, so that the different sizes of pinion 50 to mesh with the pinion 49 may be used. The pinion 50 is provided 50 with a pin 54 which extends laterally through a slot 55 in a gear 56 mounted to turn eccentrically on an eccentric extension to the same stud which carries the pinion 50. The gear 56 is in meshing engagement with gear 57 carried at the outer end of shaft 58, the inner end of which carries a beveled pinion 59, said shaft extending through a bearing sleeve 60 cast integral with the bracket 45. The beveled pinion 59 drives a similar pinion 61 on the shaft 14 whereby the cam wheel 18 is driven from ring gear 3. 55

60 Each of the units described, located around the table 1 of the knitting machine, may be driven direct from the ring gear 3 but it is not necessary that there be an individual drive for each one. The shaft 14, as shown in Figs. 2 and 5, is connected by a universal joint 62 with shafts 63 which extend to the next adjacent units whereby a single driving mechanism may be utilized to operate several of the units and drive 70 the cam wheels 18 thereof. In Fig. 1 the units at one side of the machine are driven by one power take-off construction from the ring gear 3, and those at the opposite side from another. As many of the power drive 75

take-offs from the ring gear 3 may be used as desired, though in practice two for the machine located diametrically opposite each other have proven very satisfactory.

5 With such construction of attachment, readily applied to the conventional circular knitting machine, various patterns, dependent upon the design of the cams 18, may be provided and reverse plating attained in a simple and practical manner. In Figs. 8 to 12 inclusive are shown patterns which may be made with the solid color, for instance, such as produced by the thread 43 indicated at 64 and, in Fig. 8, the lighter colors as produced by the thread 44 indicated at 65. 10 In Fig. 9 the sections 66 are the same as those indicated at 65 in Fig. 8 except for the waving outline thereof, this being produced by a difference in driving gears. The pattern in Fig. 9 is produced by a drive construction such as illustrated and described, wherein the pinion 50 drives the gear 56 through the pin and slot arrangement shown at 54 and 55. However, the stud which carries the pinions 50 and 55 together with said pinions or gears may be removed from its supporting arm 51, and two gears or pinions joined together and mounted concentrically on a stud substituted in their place, whereupon a different character of pattern with exactly the same cam wheel at 18 will be produced, the pattern showing 20 straight lines as in Fig. 8 between the two different colors of yarn or thread, while with the eccentric gearing drive described and shown in Fig. 4 the lines between the two colors will be of a wavy character.

30 35 Other driving arrangements and cams may be utilized to provide still different characters of patterns such as indicated by the solid heavier section 64 and the lighter colored section 67 in Fig. 10.

40 In Fig. 11 a pattern is indicated where the darker solid colored sections at 64 are interspersed with intermediate sections 68 in which both the solid and lighter colors are intermixed, and with other sections in which the lighter colors only appear; while in Fig. 12 the waving character of division lines between the different colored parts of the pattern is indicated in the heavy or darker colored part 64 and the lighter ones at 69, this through an eccentric drive gear construction such as shown in Fig. 4 and as described herein.

45 The adjustment of the arms 51 and 52 with respect to each provides for changing gears so that the pinions 50 and the gears 55 of different sizes may be used to drive the cam wheels 18 at different speeds with respect to the rotative speed of the ring gear 3, with a resultant change in the pattern.

50 The construction described is an attachment adapted to be readily applied to a circular knitting machine or taken therefrom when not to be used. It is of a simple, practical character and one which has been completely tested and tried out and has been used commercially with exceptionally satisfactory results. The invention is defined in the appended claims and is to be considered comprehensive of all forms of structure coming within their scope.

I claim:

55 1. An attachment for circular knitting machines comprising, a support, a shaft rotatably mounted thereon adapted to be driven by the rotating movement of the knitting machine, a cam wheel on said shaft having projecting cams, a horizontal support secured to and extending

laterally from the upper end of the first named support, rock shafts mounted on said horizontal support, levers secured one to one end of each of said rock shafts, said levers being turned in opposite directions by means of said projections on the cam wheels and yarn guides, one secured to the other end of each of said rock shafts and movable with said rock shafts on turning movement thereof, and plungers bearing against the adjacent ends of said levers for normally holding them in an initial position from which they are moved by the movement of said cam projections on said cam wheel. 5

2. An attachment for circular knitting machines comprising, a support including a lower base segment and a vertical supporting member extending upwardly therefrom, a shaft adapted to be driven mounted on said member, a second shaft located above the first shaft, a cam wheel having projecting cam portions thereon on said second shaft, means to drive the second shaft from the first shaft, a horizontal support extending from the upper end of said vertical member, rock shafts mounted thereon, levers secured one to one end of each rock shaft having parts extending from the rock shafts toward each other directly over said cam wheel, a pivotally mounted member between the cam wheel and the adjacent ends of said levers, plungers engaging against the upper sides of the adjacent end portions of said levers to hold them in a down position, and yarn guides secured one to each of said rock shafts at the other end thereof, said yarn guides each comprising an arm extending radially from its rock shaft, a bar located at right angles to said arm, and a guide sleeve at one end of said bar, the opposite end of the bar having an opening for passing the yarn therethrough. 10 15 20 25 30 35

3. An attachment for circular knitting machines comprising, a support including a lower base segment and a vertical supporting member extending upwardly therefrom, a shaft adapted to be driven mounted on said member, a second shaft located above the first shaft, a cam wheel having projecting cam portions thereon on said second shaft, means to drive the second shaft from the first shaft, a horizontal support extending from the upper end of said vertical member, rock shafts mounted thereon, levers secured one to one end of each rock shaft having parts extending from the rock shafts toward each other directly over said cam wheel, a pivotally mounted member between the cam wheel and the adjacent ends of said levers, and yarn guides secured one to each of said rock shafts at the other end thereof, said yarn guides each comprising an arm extending radially from its rock shaft, a bar located at right angles to said arm, and a guide sleeve at one end of said bar, the opposite end of the bar having an opening for passing the yarn therethrough. 40 45 50 55 60

4. In combination with a circular knitting machine, an attachment therefor mounted on said machine including two yarn guides located in proximity to the needles of the machine, one adjacent and back of the other, rock shafts on which the yarn guides are mounted, means for rocking said shafts connected with the knitting machine to be driven thereby, a second attachment of like construction secured to said knitting machine and spaced from the first attachment, and means for driving the second attachment from the first one, as specified. 65 70 75

5. In combination with a circular knitting machine, a plurality of attachments therefor located 75

around said machine in spaced relation, each of said attachments including two yarn guides, rock shafts carrying said yarn guides, means for periodically rocking the rock shafts in opposite directions to change their relative positions, means connecting all of said attachments for driving the same in unison, a ring gear on the knitting machine and means for driving all of said attachments through said connections from 10 a single driving means connected with said ring gear.

6. An attachment for circular knitting machines comprising, a support including a lower base segment and a vertical supporting member 15 extending upwardly therefrom, a shaft adapted to be driven mounted on said member, a second shaft located above the first shaft, a cam wheel having projecting cam portions thereon on said second shaft, means to drive the second shaft 20 from the first shaft, a horizontal support extending from the upper end of said vertical member, rock shafts mounted thereon, levers secured one to one end of each rock shaft having parts extending from the rock shafts toward each other 25 directly over said cam wheel, a pivotally mounted member between the cam wheel and the adjacent ends of said levers, plungers engaging against the upper sides of the adjacent end portions of said levers to hold them in a down position, and yarn guides secured one to each of 30 said rock shafts and the other end thereof.

7. An attachment for circular knitting machines comprising, a support mounted on a stationary table of the machine, a cam wheel mounted for rotation on said support, means for rotating said cam wheel, a horizontal support pivotally mounted on said support extending inwardly and over a stationary portion of the machine, yarn guides pivotally mounted on the inner end of 35 said horizontal support, means between the cam wheel and the yarn guides whereby on rotation of the cam wheel the yarn guides will be presented alternately uppermost to the needles of the knitting machine, adjusting means between 40 the horizontal support and the said stationary portion of the machine whereby the yarn guides may be adjusted vertically with respect to the 45 needles of the knitting machine.

8. The combination with a circular knitting 50 machine, of yarn guides located one above the other, said yarn guides mounted on a support, a cam wheel rotatably mounted on said support, means between the yarn guides and the cam wheel whereby, on rotation of the cam wheel, the yarn guides will be presented alternately up- 55 permest to the needles of the knitting machine,

means for driving said cam wheel comprising a ring gear on said circular knitting machine, a shaft driven therefrom, a pinion on said shaft, a second pinion driven by said first pinion, a pin projecting from said second pinion, a gear 5 eccentrically mounted with respect to said second pinion having a slot therein through which said pin passes, gearing driven by said last mentioned gear, said cam wheel driven from said gearing.

9. The combination described in claim 8 but being further characterized in that, said second pinion and said eccentrically mounted gear are mounted on an adjustable bracket whereby said pinion and said gear may be replaced by a 15 pinion and gear of another size.

10. In combination with a circular knitting machine having vertically moving needles, of 20 yarn guides located one ahead of the other in vertical planes adjacent said needles, means for mounting said yarn guides for rocking movement about horizontal axes, and means driven by the knitting machine for periodically rocking said 25 yarn guides in opposite directions to elevate the yarn carried by one guide above the other and then return it to a position below said other yarn, said driven means comprising a ring gear on said circular knitting machine, a shaft driven therefrom, a pinion on said shaft, a second pinion driven by said first pinion, a pin projecting 30 from said second pinion, a gear eccentrically mounted with respect to said second pinion having a slot therein through which said pin passes, and gearing driven by said last mentioned gear, substantially as described.

11. In a knitting machine of the class described, a table, a ring gear adapted to rotate thereon, yarn guides, yarn guide shifting means, means for constantly changing the speed of operation of the guide shifting means in a predetermined manner to make its cycle of speed recurrent, said means being operably connected to said shifting means, and means for driving the speed changing means from the said ring gear.

12. In a knitting machine of the class described, a table, yarn guides, means for movably mounting the yarn guides on the table, yarn guide shifting means and means for constantly changing the speed of operation of the guide shifting means for the purpose described, said means which constantly changes the speed operating in recurring cycles of predetermined duration.

HARRY A. SHIELDS.
